UNITED STATES PATENT OFFICE

128,437

DESIGN FOR AN ENVELOPE

Benjamin Moskowitz, New York, N. Y.

Application October 24, 1940, Serial No. 96,036

Term of patent 7 years

To all whom it may concern:

Be it known that I, Benjamin Moskowitz, a citizen of the United States, residing in the city of New York, county of Kings, State of New York, have invented a new, original, and ornamental Design for an Envelope, of which the following is a specification, reference being had to the accompanying drawing, forming part thereof.

The figure is a perspective view of an envelope embodying my design.

As shown, one of the panels on the front of the

envelope is in open position. In closed position said panel matches in appearance the panel now shown closed. Said panels comprise continuations of the front sheet of the envelope, the knobs and decorative features thereupon and adjacent thereto are mere surface ornamentation. The back of the envelope is plain.

I claim:

The ornamental design for an envelope, as shown and described.

BENJAMIN MOSKOWITZ.
